TIRE

Frederick Walter Hertzler, Detroit, Mich., assignor to
United States Rubber Company, New York, N. Y., a
corporation of New Jersey

Application May 10, 1954, Serial No. 30,396

Term of patent 14 years

(Cl. D90—20)

Fig. 1

Fig. 1 is a perspective view of a tire showing my new design, it being understood the design is repeated throughout the circumference of the sidewall of said tire;

Fig. 2 is an enlarged fragmentary side elevational view thereof;

Fig. 3 is a partial sectional view taken substantially along line III—III of Fig. 2;

Fig. 4 is a partial sectional view taken substantially along line IV—IV of Fig. 3; and

Fig. 5 is an enlarged fragmentary perspective view of the sidewall of the tire showing my new design.

The characteristic feature of the design of the tire shown resides in the combination of a sidewall provided with an outwardly projecting circumferential rib located in the region of the maximum transverse diameter of the tire, and circumferentially spaced rib-like elements substantially as shown extending radially outwardly from said circumferential rib with the outer ends thereof spaced from the tire shoulder with the area between the outer ends of said

rib-like elements and the tire shoulder substantially smooth.

I claim:

The ornamental design for a tire, substantially as shown and described.
